FOUNDATION GARMENT

Mack Kahn, Cedarhurst, N. Y., assignor to Artistic Foundations, Inc., New York, N. Y., a corporation of New York

Application June 10, 1950, Serial No. 167,325

5 Claims. (Cl. 2—37)

1

My invention relates to improvements in form-fitting foundation undergarments, and has particular reference to a novel construction for a girdle or the like.

It is an object of the invention to provide a garment of the type described which is light in weight and yet provides a firm support for the abdominal body portion of the wearer.

Another object of the invention is the provision of a garment of the type described which is constructed to conform to the anatomical structure of the wearer, providing a freedom of body movement hitherto unknown in garments of this sort.

Still another object of the invention is the provision of a garment of the type described in which the body-confining function of the garment is concentrated chiefly at the central portion of the garment corresponding to the hip and stomach region of the wearer, and in which elasticity and expansion is provided at the top and bottom of the garment for improved wearing comfort.

Other objects and advantages of the invention will be readily apparent in the course of the following specification when taken in connection with the accompanying drawings, in which,

Fig. 1 is a front elevational view of a girdle made in accordance with the invention;

Fig. 2 is a side elevational view thereof; and Fig. 3 is a rear elevational view thereof.

Referring to the drawings, the girdle shown therein is of the crotchless type, and is shown by way of example only, it being understood that the construction of the invention can be applied to a panty-girdle or other similar types of foundation undergarments.

The girdle generally comprises a front panel 10, a rear panel 11, a pair of front side panels 12 and 13, a pair of rear side panels 14 and 15, and a pair of side bottom panels 16 and 17. Front panel 10 and rear panel 11 are made of a fairly heavy material such as elastic satin which is stretchable only in a vertical direction as indicated by the directional lines in Figs. 1 and 3. Alternatively, the front and rear panels 10 and 11 may be made of an entirely non-elastic material which is not stretchable or yieldable, the front and rear panels serving merely to provide firm support for the front and rear body portions of the wearer. The front side panels 12 and 13, and the rear side panels 14 and 15 are made of elastic satin or similar stretchable material, but are arranged to stretch in various directions, as will hereinafter be described in detail.

The front panel 10 is of general rectangular

shape having substantially planar side edges 10a and 10b which extend downwardly from the top edge thereof, terminating in respective inwardly-extending arcuate lower side edges 10c and 10d. Front panel 10 may be provided with diagonal stitched pockets 18 extending from the top edge thereof to the respective side edges 10a and 10b, said pockets 18 containing the usual resilient stiffening members or stays.

10 Rear panel 11 is preferably wider than front panel 10 and is substantially wider at its lower end than at its top end, in order to provide a greater supporting and confining area at the lower portion of the garment where it is most needed. Said rear panel 11 has continuous side edges 11a and 11b extending from the top edge of rear panel 11 to the bottom edge thereof. The rear panel 11 may have an upper panel portion 19 which is stretchable in a horizontal or transverse direction, said upper panel portion 19 being stitched along its bottom edge to said rear panel 11. This upper panel portion 19 may be included to provide additional expanse or elasticity at the waist of the girdle so as to increase 15 the wearing comfort thereof. The rear panel 11 may also be provided with stay pockets 20 which are arranged similarly to the pockets 18 of front panel 10.

The front side panels 12 and 13 have respective planar front side edges 12a and 13a and planar rear side edges 12b and 13b. The front side edges 12a and 13a are respectively secured along their lengths to the side edges 10a and 10b of front panel 10, as by respective rows of open stitching 21 and 22. Optionally, a hookless slide fastener 23 may be substituted for the upper portion of one of the rows of stitching 21 or 22, as shown in Fig. 1. The front side panels 12 and 13 have respective arcuate bottom edges 12c and 13c which extend upwardly and rearwardly, and are a continuation of the curve of the respective arcuate lower side edges 10c and 10d of the front panel 10.

45 The rear side panels 14 and 15 have respective rear side edges 14a and 15a, and front side edges 14b and 15b. The rear side edges 14a and 15a are respectively secured along their lengths to the side edges 11a and 11b of rear panel 11, as well as to the respective side edges of the upper panel portion 19, by respective rows of open stitching 24 and 25.

50 The rear side edge 13b of front side panel 13 is secured along its length to the front side edge 14b of rear side panel 14 by a row of open stitching 26. Similarly the rear side edge 12b of front

side panel 12 is secured along its length to the front side edge 15b of rear side panel 15, by a row of open stitching 21.

The rear side panels 14 and 15 have respective arcuate bottom edges 14c and 15c which extend downwardly and rearwardly and are a continuation of the curve of the respective arcuate bottom edges 13c and 12c of the front side panels 13 and 12.

In the assembled position of the girdle, the lower side edge 10d of front panel 10, the bottom edge 13c of the front side panel 13, and the bottom edge 14c of rear side panel 14 form a recessed portion of substantially semi-circular shape which extends from the bottom of front panel 10 to a point adjacent the lower end of rear panel 11, as shown in Fig. 2. In a similar manner, an identical recessed portion is provided at the other side of the girdle by the respective lower side edge 10c of front panel 10, bottom edge 12c of front side panel 12, and bottom edge 15c of rear side panel 15.

These recessed portions are filled by the side bottom panels 16 and 17, which have respective arcuate upper edges 16a and 17a which conform in shape to the semi-circular edge of the recessed portion. The upper edge 17a of side bottom panel 17 is joined to the arcuate panel edges 10d, 13c and 14c, by a row of cross-stitching 28. Similarly, a row of cross-stitching 29 joins the upper edge 16a of side bottom panel 16 to the arcuate panel edges 10c, 12c and 15c. The side bottom panels 16 and 17 have respective planar rear edges 16b and 17b which are joined to the respective side edges 11b and 11a of back panel 11 by the rows of stitching 25 and 24. The bottom edges of front panel 10, rear panel 11, and side bottom panels 16 and 17, form a smooth and continuous bottom edge of the assembled girdle.

The girdle may be provided with the usual depending garters 30. An elastic band 31 may also be sewn around the inner top edge of the girdle, and an additional elastic band 32 sewn around the inner bottom edge of the girdle, in order to provide elasticity at these portions.

As was previously stated, the front and rear panels 10 and 11 are elastic or stretchable only in a vertical or longitudinal direction or may be made of non-elastic material. The front side panels 12 and 13 are stretchable in opposite diagonal directions, as indicated by the directional lines in Fig. 1. The direction of stretch of said front side panels 12 and 13 is in an upward direction from front to rear. The rear side panels 14 and 15 are also stretchable in opposite diagonal directions, as shown in Fig. 3, the direction of stretch being upward from rear to front. The side bottom panels 16 and 17 are preferably made of power-net or a similar material, so that they are stretchable in both a vertical and horizontal direction, for maximum wearing comfort. Said side bottom panels 16 and 17 may, however, be made stretchable only in a horizontal or transverse direction.

As shown in Fig. 2, the attached front side panel 13 and rear side panel 14 at one side of the girdle are stretchable in opposite directions converging upwardly at their juncture 26. The identical construction is provided at the other side of the girdle with respect to the front side panel 12 and rear side panel 15.

When the girdle is worn, the front side panels 12 and 13 stretch upwardly and rearwardly away from the front panel 10, thus pulling the front panel 10 inward along substantially its entire

length, and providing a firm support for the front body portion of the wearer, particularly at the stomach portion. In a like manner, the rear side panels 14 and 15 stretch upwardly and forwardly away from the rear panel 11, providing a firm support for the rear body portion of the wearer.

The attached front and rear side panels 13 and 14 and 12 and 15, also pull inwardly and centrally upward at the sides of the girdle, providing an effective confining force at the hip region of the wearer. Since these side panels are stretchable in diagonal directions, however, they permit freedom of movement of the body as well as comfort when sitting or standing. The side bottom panels 16 and 17 which are stretchable in a horizontal direction, and may also be stretchable in a vertical direction, provide effective confinement for the upper thigh region of the wearer, but have sufficient resiliency to allow free movement of the legs. At the same time, the degree of stretch of the side bottom panels 16 and 17 provide sufficient resiliency around the entire bottom end of the girdle to afford increased wearing comfort, the compression or inward pull of the girdle being greatest at the central portion thereof where it is most needed. The provision of the elastic side bottom panels 16 and 17 and the upper panel portion 19 of rear panel 11, provides an elasticity and expansion at the top and bottom edges of the girdle to prevent cutting at these regions.

I thus provide a girdle which is designed to conform to the anatomical structure of the human body, giving a firm and rigid support at the front and rear of the body, and providing an inward force at the sides of the body, while at the same time allowing full and free movement and change of position of the body.

While a preferred embodiment of the invention has been shown and described herein, it is obvious that numerous additions, changes and omissions may be made in the invention without departing from the spirit and scope thereof. For instance, the invention is not to be limited to the specific shape or dimension of any of the panels, since these may be varied to conform to the body dimensions of the individual wearer.

What is claimed is:

1. A foundation garment comprising a front panel and a rear panel which extend respectively from the top to the bottom of said garment and which are free from stretch in a transverse direction, respective pairs of side panels joining said front and rear panels, each pair of side panels comprising a front side panel and a rear side panel joined to each other along one longitudinal side edge, said front side panels being joined to the respective opposite longitudinal side edges of said front panel and being stretchable in a diagonal direction upwardly and away from said front panel, said rear side panels being joined to the respective opposite longitudinal side edges of said rear panel and being stretchable in a diagonal direction upwardly and away from said rear panel, each pair of side panels extending from the top of said garment to a short distance below the center of said garment, and together presenting a continuous concave bottom edge, and a bottom side panel joining the lower portions of said front and rear panels on each side of the garment, each bottom side panel having a convex upper edge matching and secured to the concave bottom edge of a respective pair of side panels, each of said bottom side

panels being stretchable in a transverse direction.

2. A foundation garment according to claim 1 in which said bottom side panels are stretchable both transversely and longitudinally.

3. A foundation garment comprising a front panel and a rear panel which extend from the top to the bottom of said garment, are stretchable only in a longitudinal direction, and are sized and positioned to cover respectively the abdomen and lower back region of the wearer, respective pairs of side panels joining the front and rear panels, each pair of side panels comprising a front side panel and a rear side panel joined to each other along one longitudinal side edge, said front side panels being joined to the respective opposite longitudinal side edges of said front panel and being stretchable in a diagonal direction upwardly and away from said front panel, said rear side panels being joined to the respective opposite longitudinal side edges of said rear panel and being stretchable in a diagonal direction upwardly and away from said rear panel, each pair of side panels having a top edge coinciding with the top of the garment and a continuous concave bottom edge spaced above the bottom of the garment to confine the side waist and hip region of the wearer, and a bottom side panel at each side of the garment joining the lower portions of said front and rear panels and having a bottom edge coinciding with the 30

bottom of the garment and a convex top edge matching the concave bottom edge of the respective pair of side panels and secured thereto, each of said side panels being stretchable in a transverse direction, and covering the outer thigh region of the wearer.

4. A foundation garment according to claim 3 in which said bottom side panels are stretchable in both a transverse and longitudinal direction.

5. A foundation garment according to claim 3 in which the lower side edge of said front panel extends arcuately inward toward the center of the front panel to the bottom edge thereof, the concave edge of each bottom side panel extending along said arcuate lower side edges and being secured thereto.
